UNITED STATES PATENT OFFICE.

PETER THOMSEN, OF CASSEL-WILHELMSHÖHE, GERMANY, ASSIGNOR TO SCHMIDT'SCHE HEISSDAMPF-GESELLSCHAFT MIT BESCHRANKTER HAFTUNG, OF CASSEL, GERMANY, A CORPORATION OF GERMANY.

STEAM-SUPERHEATER.

1,074,300.

Specification of Letters Patent. Patented Sept. 30, 1913.

Application filed October 29, 1912. Serial No. 728,371.

To all whom it may concern:

Be it known that I, PETER THOMSEN, a subject of the King of Prussia, Emperor of Germany, residing at Cassel-Wilhelmshöhe, Germany, have invented a certain new and useful Improvement in Steam-Superheaters, of which the following is a specification.

My invention relates to steam superheaters for locomotive- and like boilers. The 10 superheater pipes in the type referred to are arranged in fire tubes usually of enlarged diameter and the object of the present invention is to prevent overheating of the superheater pipes under certain working conditions when no steam is passing through them.

The invention consists in arranging at the saturated steam header or its supply pipe a non-return valve or the like which is 20 closed when steam is passing through the superheater and which opens when the steam is shut off so that when the engine is running with steam shut off, air will be drawn through the superheater to cool the tubes.

25 The invention also consists in the improved superheaters hereinafter described or indicated.

Such valves are usually arranged on the valve chest or steam admission pipe of the 30 engine, their object being to admit air into the cylinders when the engine is running with steam shut-off, so as to prevent a braking action. By their new disposition, however, they are enabled to perform not only 35 their original function but also the additional function of preventing overheating of the superheaters.

The accompanying drawing illustrates one 40 form of the present invention. In carrying the invention into effect according to this form, the superheater is shown applied to a locomotive, the boiler of which is indicated at *a*, the superheater pipes *f*, passing from a saturated steam header or chamber *d* into 45 the enlarged smoke tubes *b* and so to the superheated steam header or chamber *e*. The chamber *d* is supplied with steam from the boiler in the usual manner through a regulator or throttle (not shown) controlling the flow of steam through a main steam pipe opening into the chamber *d*.

A chamber is provided in connection with the saturated steam collector or header *d*.

This chamber may be formed, for instance, by the valve seat on the end of a pipe *k*, 55 connected to the saturated steam collector, and a cap *n*, screwing over the valve seat and open to the atmosphere. In this chamber a suitable valve such as a ball valve *l* is arranged. As long as the engine receives steam through the superheater, the ball is forced upward and so prevents access of air to the superheater. If, however, steam is 60 shut off, while the engine is running, the ball falls and rests on the valve seat above 65 mentioned, which, as shown in the drawing, is provided with ports *p* in such a manner that they cannot all be closed by the ball. As the piston reciprocates in the cylinder 70 therefore air is sucked in past the valve and through the superheater pipes, thereby assisting to prevent over-heating.

It will be evident that the invention is in no way restricted to any particular form of non-return valve, that described above being 75 merely by way of illustration of the present invention.

Having described my invention, I claim:

1. In a smoke tube boiler, superheater pipes in some of the smoke tubes, steam 80 supply means connecting the boiler to the superheater pipes, and a valve in said steam supply means adapted to be opened or closed as to the atmosphere.

2. In a smoke tube boiler, superheater 85 pipes in some of the smoke tubes, steam supply means connecting the boiler to the superheater pipes, and a valve in said steam supply means opening to the atmosphere, 90 said valve having means controlled by the steam pressure in said supply means for closing said valve.

3. In a boiler of the class described having a superheater provided with a saturated steam header, a superheated steam header, 95 and superheater pipes connecting said headers, an opening to the atmosphere between the boiler and the superheater pipes and means controlled by the steam pressure for closing said opening.

4. In a boiler of the class described having a superheater provided with a saturated steam header, a superheated steam header, 100 and superheater pipes connecting said headers, a valve open to the atmosphere between the boiler and the superheater pipes, 105

said valve having automatic means controlled by the steam pressure whereby said valve is closed.

5. In a boiler of the class described having a superheater provided with a saturated steam header, a superheated steam header, and superheater pipes connecting said headers, a valve opening into the saturated steam header, and having automatic means 10 for opening to the atmosphere when the steam pressure is on and for closing to the atmosphere when the steam pressure is off.

6. In a boiler of the class described having a superheater provided with a saturated steam header, a superheated steam header, and superheater pipes connecting said headers, a non-return valve normally connecting the saturated steam header with the atmosphere and means actuated by the 20 steam pressure for closing said valve.

7. In a boiler of the class described having a superheater provided with a saturated steam header, a superheated steam header, and superheater pipes connecting said headers, the combination of a pipe opening 25 into the saturated steam header and having a ball normally resting upon the end of said pipe and incompletely closing the same, and a cap loosely embracing said ball and attached to the end of said pipe, said cap 30 having an opening to the atmosphere and said ball being adapted to be moved by the steam pressure to close said cap opening.

In testimony whereof, I have hereunto set my hand in the presence of two subscribing witnesses.

PETER THOMSEN.
